UNITED STATES PATENT OFFICE.

LAUREN S. BEARDSLEY, OF NAUGATUCK, CONNECTICUT.

DESIGN FOR AN INSULATOR-HOLDER.

SPECIFICATION forming part of Design No. 24,249, dated April 23, 1895.

Application filed January 12, 1895. Serial No. 534,714. Term of patent 7 years.

To all whom it may concern:

Be it known that I, LAUREN S. BEARDSLEY, a citizen of the United States, residing at Naugatuck, in the county of New Haven and 5 State of Connecticut, have invented a certain new and useful Design for Insulator-Holders, of which the following is a specification.

I have illustrated my design in the accompanying drawings, forming part of this specification, and in which—

Figure 1 is an elevation of an insulator holder of my design. Fig. 2 is a cross-section on the line $x-x$, Fig. 1.

The leading and characteristic feature of 15 my design is the shape of the main portion of the holder A—between the outer end a^2 and

the base B which is expanded. This central portion of the holder is cylindrical in cross-section and has upon its outer surface a number of longitudinally arranged radial ribs a^3 . 20

What I claim is—

The design for an insulator holder, substantially as shown and described.

In testimony whereof I have hereunto affixed my signature, in the presence of two witnesses, at the city, county, and State above written, this 31st day of December, 1894. 25

LAUREN S. BEARDSLEY.
